UNITED STATES PATENT OFFICE

HEINRICH STRIEFFLER, OF LANDAU, GERMANY

AIRSHIP MAST

Application filed August 14, 1930. Serial No. 475,172.

The present invention relates to an air-ship mast, the essential feature of which is that it has a head provided with fastening means for the anchoring of an air-ship, and in which the supporting pillar is inclinable in all directions under the control of resilient forces. At the same time the head can be turned in all directions as required. The supporting pillar has at its foot a joint allowing of a similar movement in all directions, and such pillar is held taut by means of tensioning devices which incorporate springs. The mast-head is preferably constructed as a platform, and is provided with a cover for protection from the wind, which cover can take the form of an elastic buffer. The foot of the mast may be situated in a suitable manner on spring members yielding in the direction of the longitudinal axis of the mast. It is particularly advantageous if the pivoted head of the mast protrudes through the wind-protection cap to be located between its bearing surface and its apex. In a further embodiment the foot of the mast is attached to a girder which can be rotated on a vertical axis and may be swung round a horizontal axis, and the head of the mast is directed downwards, in which case the girder is borne by a second mast.

In the drawings the invention is illustrated by way of example in various embodiments.

Figures 1 and 2 show in plan the known means of fastening an air-ship to the point of a rigidly anchored mast.

Figure 3 is an elevation and

Figure 4 a plan of a simple embodiment of an air-ship mast according to this invention.

Figure 3a shows another design of the top of the mast.

Figure 5 is a plan corresponding to Figure 4 of a mast provided with a wind-protection cap.

Figures 6, 7, 8 and 9 are elevations of air-ship masts fitted with wind-protection caps according to the invention, and

Figure 10 is a side view of a further improved embodiment, of which the construction is diagrammatically represented in Figure 11.

Figures 12, 13 and 13a show two different embodiments of a part of a mast hereinafter referred to.

Figure 1 shows in plan a known method of anchoring of the nose 1 of an air-ship by means of a securing cable 2 to a shock absorber 4 placed so that it may swing at the summit 3 of the air-ship mast. When sudden gusts of wind from the side (arrows A) occur, with such a method of anchoring, the shock absorber is swung from its position I into position II, while the body of the air-ship, owing to the inertia of its great bulk, is merely displaced in a parallel direction. As a result of this, great strains are set up at the point where the securing cable is fastened to the air-ship, these strains being prejudicial and frequently causing disturbances such as the snapping of the cable or breaking off of the nose of the air-ship. For this reason a method has already been tried by making provision for a revolving wind-protection cap 5 (see Figure 2) enclosing the shock absorber 4 into which cap is guided the nose of the air ship, which is fastened to the securing cable of the shock absorber. In this case also the longitudinal axes of the wind-protection cap and the air-ship are caused to vibrate in relation to one another when gusts of wind (arrow A) suddenly occur, so that the rim of the cap presses into the nose of the air-ship (see position II Figure 2) and the anchoring cable is broken off.

By the present invention these defects are avoided. The simplest embodiment of the new air-ship mast is shown diagrammatically in Figures 3 and 4. The mast 6, which may be constructed from a rigid tube, is provided at its foot with a ball 7 mounted in a socket 8. At its head, which is suitably provided with a platform 9 wire cables or similar tensioning devices 10 are fixed there-around, which wire cables are anchored to the ground in a circular disposition, and thus hold taut the mast 6. Springs 11 are inserted in the tensioning devices, which springs permit an elastic yield of the mast in all directions. At the top of the mast, the air-ship 1 is fastened with the aid of a securing cable 2 which passes over a pulley 26. The pulley

26 can also be replaced by a funnel-shaped construction of the mast head which has a beaded edge for guiding the securing cable, as shown by Figure 3a. A suitable spiral staircase 12 or the like winds around the mast from the ground to the top, and terminates in an upper platform 9 from which one can mount the air-ship by a step 25. The ordinary position of rest of the mast with the anchored air-ship is shown in full lines Figure 4. On the sudden occurrence of powerful gusts of wind (direction shown by arrow A) the mast bends with the wind, and the air-ship is displaced in a position practically parallel to its original position, so that mast and air-ship take the position shown by dotted line in Figure 4 where they are in the same favourable relative position to each other as before the bending of the mast. Thus no prejudicial strains on the securing members are set up in this case.

Figure 5 shows a further embodiment according to which a wind-protection cap 5, which is suitably constructed of a light metal, and which receives the nose of the air-ship, is placed so that it may revolve at the top of the mast 6 which is flexible in all directions under the control of elastic forces; and in this cap the anchoring cable 2 is attached to a shock absorber 4. From the top of the mast, securing cables 10 pass radially and downwardly in all directions which cables are anchored to the ground and are fitted with tension springs. In this case also the mast is able, in the case of gusts of wind suddenly coming from the side, to bend with the wind, and thus it can yield with the body of the air-ship together with the wind protection cap by means of which action unfavourably acting forces are eliminated. As a result of this construction the whole air-ship mast also functions as a giant "buffer" when the air-ship bumps, and resiliently yields in all directions. In the wind-protection cap itself buffers of any desired kind may be also fitted.

In the case of the embodiment shown in elevation in Figure 6, the supporting column 14 of the air-ship mast is formed of a girder construction rectangular in plan, and has a lower ball 15 resting in a ball socket 16. The socket 16 is supported, with a level bed-plate 17, on compression springs 18 which enables an elastic downward movement of the mast to be obtained in the direction of its longitudinal axis. To the top platform 19 of the mast are secured the fastening cables 10 which are anchored to the ground at the other end in a circular arrangement around the mast, tension springs being incorporated therewith.

The tension springs are fitted in special casings 20 and these sometimes receive, as is shown in a large scale drawing in Figure 12, several springs of different strengths for the

purpose of withstanding shocks of different and varying strength, as occur, for example with air-ships of different sizes. Upon an upper pivot 21 of the supporting column, a frame of girder construction is rotatably mounted which frame on the one side takes the form of a wind-protection cap 22 and on the opposite side 23 carries a balance weight 23a. A spiral staircase 24 round the supporting column 14 leads to the platform 19 from which a step or gangway 25 leads out through the wind-protection cap, with which it is rotatable, into the nose of the air-ship. The nose of the air-ship is attached by securing cable 2 which is passed over a pulley 26 to the windlass 28 situated at the bottom of the supporting column. In this case also the air-ship mast can bend in any direction should gusts of wind occur, and, moreover, it can also yield in an axial direction against the influence of the compression springs 18 if it receives vertical buffets from the wind. Likewise, the whole mast functions, in the case of any blow from the air-ship on the wind-protection cap, as an elastic buffer, which can even be furnished with flexible shock absorbers.

The embodiment according to Figure 7 differs from those previously described in the first place in that the air-ship mast is constructed as a double column. An outer column 29 rests by means of a lower ball 29a in a bearing socket 30 and carries at its upper end a platform 31, on which is mounted a rigid platform 31a; the securing cables 10 are connected to the platform 31 and incorporate the elastic spring members 20. In this exterior swinging column an inner column 32 is rotatably mounted, and the lower pivot 33 is received in a bearing 35 of the outer column, and bears on a spring 34. The upper end of the outer column 29 is rotatably connected to the inner column 32 through balls 29b. The upper end of the inner column, which projects above the outer column 29 forms a vertical pivot 32a on which the wind-protection cap 35, which is of girder-construction, is rotatably mounted. At the same time, in this case, the vertical axis 32a crosses the longitudinal axis of the wind-protection cap at about the middle of the length of the latter, so that the inner surface 105 of the wind-protection cap lies on the one side of the vertical axis 32a, and the point 110 on its other side, whereby the wind-protection cap rests in equilibrium. Further, that surface of the half of the cap on the air-ship side of the axis 32a which is set against the wind pressure, is somewhat larger than the surface of the half of the cap which forms the point of the wind-protection cap and, in fact, so much so, that the cap can automatically set itself in the direction of the wind. The windlass 28 is fixed on the bottom of the inner column 32 and a cable

2 is passed over the top pulley 26 to the nose of the air-ship 1. Similarly, a step or gangway leads from the nose of the air-ship into the wind-protection cap, which step can be revolved with the wind-protection cap, and which borders closely on the platform 31a. A spiral staircase 24 which encircles the outer mast, leads to the platform 31a, or a staircase or ladder fitted in the inner mast may be utilized.

Figure 8 shows a particularly simple embodiment of the air-ship mast with inner and outer columns similar to Figure 7. In this case the inner column 32b is inclinable in all directions through a lower ball joint 70, while at the same time the mast is rotatable through the medium of a suitable bearing socket 71. The outer column is reduced to a collar 76, which is mounted on the inner column 32b by means of balls 72 and which is supported by ball bearings 74 on a bearing ring 75 of the inner column. To this collar 76 are again attached the elastic securing cables 10 which encircle the mast. In the base of the inner column the windlass 28 is situated, the cable 2 of which windlass passes over the pulley 26 at the top of the mast to the air-ship. The inner column has at its head a rectangular and rigidly fixed frame 78, which takes the form of a wind-protection cap, and which is provided with a step or gangway 77, which leads from the column 32b and to the entrance of the air-ship. One arrives at the step 77 by a spiral-staircase 79 which is merely secured to the column 32b, and which runs partly outside and partly inside the column. The mast, step or gangway and wind-protection cap form in the present case one rigidly constructed unit, but at the same time the rotatability of the mast-top, together with the inner column 32b, as also the ability of the mast to incline in all directions, together with the upper collar 76 which represents the outer column, is ensured in every way. An embodiment of this kind of air-ship mast is, of course, also possible without wind-protection cap.

A further modification of the construction of the air-ship mast, according to the present invention, is shown in Figure 9. In this case the mast 80 rests with its ball pivot 81 in a socket 82 in a pit 83. The mast 80 which is approximately square in cross-section, carries the ring 84 of a ball bearing, between the outer ring of which and the pit walls radially arranged coil springs 86 are fitted, which maintain the mast 80 in equilibrium, but which also allow of an elastic yielding of the same in all directions. The pit 83 is covered up by a plate 87 which has an opening to permit of the swinging movement of the mast. Around the mast runs a stairway 88 to the wind-protection cap 89 which is fixed rigidly on the top of the mast, which

wind-protection cap is connected to the air-ship by means of a step or gangway 90. In this type of construction by virtue of the introduction of the elastic tensioning members in the pit, no stay members protrude above the ground, so that the service to or from the air-ship for landing and starting is in no way hindered.

The embodiment shown in Figure 10 is also represented diagrammatically in Figure 11 in order to make the principles of construction easily evident. The mast 40 which carries the wind-protection cap 39 is suspended from a girder 41 with its head downwards and its jointed foot upwards, and such girder is carried by a second mast 42. In this case also the mast 40 is firmly held by elastic tensioning devices to the girder 41 to enable it to yield in all directions. In the case of the embodiment according to Figure 10 the girder mast 42 ends in a platform 43, which is reached by a stairway 44 or by a lift. A hood 45 may be revolved around the platform 43 and such hood is supported on upper ball bearings 46 and side rollers 48 bearing against a frame 47 under the platform. On a pivot 49 of the hood head, a girder 41 is disposed in a manner permitting it to swing about a horizontal axis, and springs 52 are arranged between the girder 41 and the lateral stops 45a on the hood 45 for the purpose of restricting the swinging motion. Near the ends of the girder 41 are suspended in ball joints 50 masts 51 which project downwards, and which receive a step or gangway 53 at the lower joint 90. This gangway 53 carries by means of stays 58 the wind-protection cap 59. The masts 51 are held in tension by several coil springs 54 fixed to the girder 41, sometimes in circular formation. The bearings of the ball joints 50, are suspended on the supporting pins 55 which are supported by the bearing plates 56 on the compression-springs 57 which are supported by the girder. The step or gangway 53 encircles the hood 45 with an intervening space, except for a bridge connection 60, which is attached to the hood at one side, and which borders at its inner end against the inner platform 43 of the mast 42 in every position of the hood, and which opens at its outer end into the forepart of the rotatable and inclinable step or gangway 53. On the step or gangway 53 is situated the windlass 61; the nose of the air-ship is anchored to the securing cable 2 which runs from the windlass, and the opening in the nose of the air-ship is connected with the gangway over the bridge 62. The wind-protection cap 59 can automatically adapt itself to the particular direction of the wind, by virtue of the suspension of its supporting members about a vertical axis. Upon the occurrence of gusts of wind from the side, the cap yields correspondingly with the air-ship in the direction 130

of the wind, and, in fact, as a result of the suspension of the gangway 53 which supports the wind-protection cap to the mast, by which suspension the gangway is elastic in all directions under the control of springs, the intervening space left free between the bridge 53 and the hood 45, permitting swinging movements in every way. Thus the whole device functions as a giant elastic buffer, should the air-ship bump when being moored on the air-ship mast.

The compression-springs 54 can also be replaced by rigid or inelastic means of support, such as wire cables, into which simple or compound yielding spring members are inserted. The compound spring member represented in Figure 12 on a large scale, as an example of embodiment, consists of an extended two-piece casing 20a, 20b at one narrow end of which is an aperture 65a. Through this projects a stem 65 which passes through the casing, and which has, both at its inner end and at the middle of its length a supporting plate 66. Between the supporting plates is a compression-spring 67 wound round the stem; between the middle supporting plate and the casing wall with the aperture, is a more powerful coil spring 68. When the tension cable 10 is pulled at the eye 69 of the stem which passes through the casing, when the casing is anchored to the ground with its eye 64, the less powerful coil spring 67 is compressed first. Only when a certain more powerful strain is applied does the stronger spring 68 come into action.

A device may also be provided according to which springs of varying strengths are mechanically put into or put out of action in the securing cables. Figures 13 and 13a show such an embodiment of a compound spring member. To the one end of the casing 91, with double spring which approximately corresponds to Figure 12, two further casings 93 and 94 are attached in link eyes 92, which casings may be pushed by slotted securing members 95, 95a (see Figure 13a view in direction of the arrow G of Figure 13) at their opposite end over a stop 96 of the rod 97 which passes through the casing 91. The one side casing 93 receives an internal spiral spring 98 which at one side abuts against the end of the casing and at the other side bears on a supporting plate 99a of a draw-rod 99, which passes through the casing and carries the upper slotted securing member 95. When the casing 93 is folded over in the direction of the arrow E the spring 98 is connected to the springs of the casing 91 so that suitable provision is made in case particularly heavy strains occur as are likely with the larger types of air-ships. The other side housing 94 contains a spindle 101 which rotates in the coupling 100. The upper end of the spindle carries a slotted securing member 95a which may similarly

be closed on the stop 96. If this casing 94 is swung in the direction of the arrow F and the securing member is moved over the central shaft 97 the elastic spring forces are completely eliminated and a tug at the cable attached to the shaft 97 has a direct effect on the lower rigid anchorage by way of the rigid casing 94. Such a method of cutting out the elastically yielding members may be desirable when there is no danger of any forces attacking the air-ships, and through it the mast to which it is moored.

The various embodiments of the air-ship masts may also be constructed in a portable manner, so that they may be used as driving appliances for running air-ships into hangars.

Claims:

1. An air-ship mast comprising a supporting column adapted to be inclined as a whole in any direction under control of elastic forces, and securing means on the head of the mast for anchoring the air-ship.

2. An air-ship mast having a head rotatable in all directions about a vertically directed axis, securing means on said head for anchoring the air-ship, and a supporting column adapted to be inclined in any direction under the control of forces normally returning the column to its vertical position.

3. An air-ship mast having a head rotatable in all directions about an axis normally vertical, securing means on said head for anchoring the air-ship, a supporting column having a joint at its foot to allow the column to incline as a whole in any direction, and spring tensioning devices to resiliently hold said column in vertical position.

4. An air-ship mast having a head rotatable in all directions about an axis normally vertical, securing means on said head for anchoring the air-ship, a gangway incorporated with said head, a wind protection shield on said head, a supporting column having a joint at its foot to allow said column to incline in any direction, and spring tensioning devices to resiliently hold said column in position.

5. An air-ship mast having a head rotatable in all directions about an axis normally vertical, securing means on said head for anchoring the air-ship, a gangway incorporated with said head, a wind-protection shield on said head, a supporting column having a joint at its foot to allow said column to incline in any direction, spring tensioning devices to resiliently hold said column in position, and a resilient support for said column so that it is movable under spring control in the direction of its vertical axis.

6. An air-ship mast having a head rotatable in all directions about an axis normally vertical, a bridge or gangway incorporated with said head, a wind-protection shield on said head, arranged so that the said axis passes between its bearing surface and peak, secur-

ing means on said head for anchoring the air-ship, a supporting column having a joint at the foot to allow said column to incline in any direction, spring tensioning devices to resiliently hold said column in position, and a resilient support for the said column so that it is movable under spring control in the direction of its vertical axis.

7. An air-ship mast having a head rotatable in all directions about an axis normally vertical, a bridge or gangway incorporated with said head, a wind-protection shield on said head arranged so that the said axis passes between its bearing surface and peak, and so 15 that the surface exposed to the wind pressure on the front side or air-ship side of the axis is larger than that on the rear side of the axis, and securing means on said head of the mast for anchoring the air-ship.

20 8. An air-ship mast having a head rotatable in all directions about an axis normally vertical, a bridge or gangway incorporated with said head, a wind-protection shield on said head arranged so that the said axis 25 passes between its bearing surface and peak, and so that the surface exposed to the wind pressure on the front side or air-ship side of the axis is larger than that on the rear side of the axis, securing means on said head for 30 anchoring the air-ship, a supporting column having a joint at the foot to allow said column to incline in any direction, spring tensioning devices to resiliently hold the column in position, and a resilient support for the 35 said column so that it is movable under spring control in the direction of its vertical axis.

9. An air-ship mast having a head rotatable in all directions about an axis normally vertical, a bridge or gangway incorporated 40 with said head, a wind-protection shield on said head arranged so that the said axis passes between its bearing surface and peak, securing means on said head for anchoring the air-ship, a supporting column having a 45 joint at the foot to allow said column to incline in any direction, spring tensioning devices, having springs of unequal strength, to resiliently hold said column in position, and a resilient support for the said column so 50 that it is movable under spring control in the direction of its vertical axis.

10. An air-ship mast having a head rotatable in all directions about an axis normally vertical, a bridge or gangway incorporated 55 with said head, a wind-protection shield on the head arranged so that the said axis passes between its bearing surface and peak, securing means on said head for anchoring the air-ship, a supporting column having a joint 60 at the foot to allow said column to incline in any direction, spring tensioning devices to resiliently hold said column in position, auxiliary spring devices for combining with the said spring tensioning devices to increase 65 the strength, means for combining with the

said tensioning devices for cutting out the spring action, and a resilient support for the said column so that it is movable under the spring control in the direction of the vertical axis.

11. Air-ship mast having a head rotatable in all directions about an axis normally vertical, a bridge or gangway incorporated in said head, a wind-protection shield on the head so arranged that the said axis passes 70 between its bearing surface and peak, securing means for anchoring the air-ship, a supporting column formed of several parts, a joint at the foot of said supporting column to allow said column to incline in any direction, spring tensioning devices to resiliently hold said column in position, and resilient supporting means so that said column is movable under spring control in the direction of its vertical axis.

12. Air-ship mast having a head rotatable in all directions about an axis normally vertical, a bridge or gangway incorporated in said head, a wind-protection shield on said head so arranged that the said axis passes 75 between the bearing surface and peak, securing means for anchoring the air-ship, a supporting column formed of two parts one of which is rotatable in relation to the other, a joint at the foot of said column to allow said column to incline in any direction, elastic tensioning devices for holding said column in position connected to the non-rotatable part of said column, and resilient supporting means so that said column is movable 80 under spring control in the direction of its vertical axis.

13. Air-ship mast having a head rotatable in all directions about an axis normally vertical, a gangway incorporated in said head; a wind-protection shield on said head so arranged that the said axis passes between its bearing surface and its peak, securing means for anchoring the air-ship, a mast mounted 90 so that it can incline in any direction, spring tensioning devices for holding said mast in position, means whereby said mast is resiliently movable in the direction of its longitudinal axis, a girder from which the said mast is suspended in an inverted position, and a second mast on which the said girder is 95 rotatably mounted.

14. Air-ship mast having a head rotatable in all directions about an axis normally vertical, a gangway incorporated in said head, a wind-protection shield on said head so arranged that the said axis passes between its bearing surface and its peak, securing means for anchoring the air-ship, a mast with spring tensioning devices for holding the said mast 100 in position and allowing the said mast to incline in any direction, a spring bearing whereby the said mast is movable in a longitudinal direction, a girder from which the 105

- said mast is suspended in an inverted position, and a second mast on which the said girder is rotatably mounted and also mounted to rotate about a horizontal axis under spring control.
15. Air-ship mast having a head rotatable in all directions about an axis normally vertical, a gangway incorporated in said head, a wind-protection shield on said head so arranged that the said axis passes between its bearing surface and its peak, securing means for anchoring the air-ship, a mast with spring tensioning devices for holding the said mast in position and allowing the said mast to incline in any direction, a spring bearing whereby the said mast is movable in a longitudinal direction, a second mast, a hood rotatable round the head of the second mast, a girder mounted to rotate about a horizontal axis on said hood and on which the first mentioned mast is suspended in an inverted position and compression springs bearing on lateral stops on said hood and also bearing against said girder.
25. 16. Air-ship mast having a head rotatable in all directions about an axis normally vertical, a gangway incorporated in said head, a wind-protection shield on said head so arranged that the said axis passes between its bearing surface and its peak, securing means for anchoring the air-ship, a mast mounted so that it can incline in any direction, a spring bearing whereby the said mast is movable in a longitudinal direction, spring tensioning devices for holding the mast in position and allowing the mast to incline in all directions, a second mast, a hood rotatable round the head of the second mast, a girder mounted to rotate about a horizontal axis on said hood and on which the said first mentioned mast is suspended in an inverted position, compression springs bearing on lateral stops on said hood and also bearing against said girder, a platform on the said second mentioned mast, and a stairway leading from the ground to the platform.
17. An air-ship mast having a head rotatable in all directions about a normally vertical axis, a wind-protection shield so arranged that the said axis passes between its bearing face and its apex, means for anchoring said air-ship carried by the head, a mast which is mounted so that it may incline in any direction, tensioning devices to resiliently hold said mast in position, a spring bearing in which the said mast is mounted so that it is resiliently movable in the direction of its longitudinal axis, a girder which supports the said mast in an inverted position, an annular gangway carried by the said mast, a second mast, a hood rotatably mounted at the head of the second mast and on which the said girder is pivotally mounted, a platform on the top of said second mentioned mast and a bridge carried by said hood which bridges the space between the said platform and the annular gangway.
18. An air-ship mast having a head rotatable in all directions about a normally vertical axis, a wind-protection shield so arranged that the said axis passes between its bearing face and its apex, means for anchoring the air-ship carried by said head, a mast which is mounted so that it may incline in any direction, tensioning devices to resiliently hold said mast in position, a spring bearing in which the said mast is mounted so that it is resiliently movable in the direction of its longitudinal axis, a girder supporting the said mast in an inverted position, an annular gangway carried by the said mast, and a windlass or anchoring attachment carried by said annular gangway.
19. An air-ship mast having a head rotatable in all directions about a normally vertical axis, a wind-protection shield so arranged that the said axis passes between its bearing face and its apex, means for anchoring the air-ship carried by said head, a mast which is mounted so that it may incline in any direction, devices to resiliently hold said mast in position, a spring bearing in which the said mast is mounted so that it is resiliently movable in the direction of its longitudinal axis, a girder supporting the said mast in an inverted position, an annular gangway carried by the said mast, a windlass carried by said annular gangway, stays carried by said annular gangway and supporting said wind-protection shield enclosing said mast and said girder.
- In witness whereof I have signed this specification at Frankfort A/M, Germany, this 28th day of July, 1930.
- HEINRICH STRIEFFLER.
